(57) **CLAIM**

The ornamental design for a personal flotation device, as shown.

DESCRIPTION

FIG. 1 is a perspective view of a personal flotation device showing my new design;

FIG. 2 is a front elevational view of the personal flotation device of FIG. 1;

FIG. 3 is a back elevational view of the personal flotation device of FIG. 1;

FIG. 4 is a right side elevational view of the personal flotation device of FIG. 1;

FIG. 5 is a left side elevational view of the personal flotation device of FIG. 1;

FIG. 6 is a top plan view of the personal flotation device of FIG. 1; and,

FIG. 7 is a bottom plan view of the personal flotation device of FIG. 1.
